S. F. JONES,

Windlass Water-Elevator.

No 44,371.

Patented Sept. 20, 1864

Inventor:

Samuel F. Jones

UNITED STATES PATENT OFFICE.

SAMUEL F. JONES, OF ST. PAUL, INDIANA, ASSIGNOR TO HIMSELF AND
ERASTUS L. FLOYD.

IMPROVEMENT IN WATER-ELEVATORS.

Specification forming part of Letters Patent No. 44,371, dated September 20, 1864.

To all whom it may concern:

Be it known that I, SAMUEL F. JONES, of St. Paul, in the county of Decatur and State of Indiana, have invented a new and Improved Water-Elevator; and I do hereby declare that the following is a full, clear, and exact description of the construction and operation of the same, reference being had to the accompanying drawings, and to the letters of reference marked thereon.

Figure 1 is a perspective view. Fig. 2 is a side central view of the water-elevator constructed according to my invention. Fig. 3 is a detail drawing showing the forked-lever F, and Fig. 4 is a detail drawing of the friction-block C.

The nature of my invention consists in the novel arrangement of the adjustable spout B, friction-block C, stationary pin m, and the forked-lever F, as hereinafter fully described.

To enable those skilled in the art to make and use my invention, I will proceed to describe its construction and operation.

The curb A is the ordinary size of water-elevators. The front G is straight. The back is sloped inward from the bottom. The spout B is supported at the front end by the friction-rollers ee in the block C, Fig. 4, and is guided by the pin i in the groove L. The pin m is placed near the inside end of the spout and projects above the spout. By this pin the valve v is elevated. The lever F is forked. One prong is passed down on each side of the front end of the spout about three inches from the end, and is secured to the side of the spout by screws. The fulcrum of the lever is formed by the forked pin n in Fig. 2. This pin is secured to the front-board by the tap n', Fig. 1. The prongs of the lever F are bent, as shown in Fig. 3. The lever is bent as shown at the forked pin n, Fig. 2. The bucket D is an ordinary well-bucket, provided with a metal bottom. There is a hole in the center of the bottom, in which the valve v operates. The leather on the valve projects back and is attached to the block r, which is secured to the bottom of the bucket by means of screws. The valve is turned round, with a flange, a, which projects and rests on the bot-

tom of the bucket. The under part of the valve is oval, and projects below the bottom of the bucket. The leather is tacked on the flange and around the projection. The bucket D is attached to one end of the rope k and the weight H to the other. The rope k rests in a V-shaped groove in the wheel E. This wheel is turned by an ordinary crank, J, Fig. 1, the axle of which rests on bearings f. The bar I is designed to stop the bucket, when ascending, at a proper height for the pin m to elevate the valve v. By the boards P and u the top of the curb is raised to a proper height. x is a sheet-iron cover. The block C, Fig. 4, is attached to the curb under the spout, as shown in Fig. 1.

The operation of my water-elevator is as follows: The operator takes hold of the lever F by the handle h and pushes it toward the wheel E. This throws the spout out until the prongs b b of the lever strike the inside of the front of the curb. The bucket is then let down into the well and fills immediately through the valve. It is then drawn up until the bail strikes the bar I. The lever is then drawn outward into the slot S, Fig. 1. This thrusts the spout into the curb and under the bucket. As the spout is being thrust into the curb, the inside end rises until the pin m strikes the valve and elevates it, and the water is discharged through the bottom of the bucket into the spout and thence into the vessel below.

Having thus fully described the construction and operation of my invention, what I claim as new, and desire to secure by Letters Patent, is—

1. The sliding spout B, pin m, and bucket D, arranged substantially as described.
2. In combination therewith, the lever F, substantially as described.
3. Operating a discharge-valve in a well-bucket by thrusting a trough laterally beneath the said bucket to elevate the said valve, substantially as shown and described.

SAMUEL F. JONES.
